UNITED STATES PATENT OFFICE.

EDWIN L. EDWARDS, OF INDIANAPOLIS, INDIANA, ASSIGNOR TO EDWARDS X-RAY CORPORATION, OF INDIANAPOLIS, INDIANA, A CORPORATION OF INDIANA.

AUTOMATIC ELECTRICAL CIRCUIT CONTROLLER.

Application filed April 15, 1920. Serial No. 374,191.

To all whom it may concern:

Be it known that I, EDWIN L. EDWARDS, a citizen of the United States, residing at Indianapolis, in the county of Marion, and 5 State of Indiana, have invented a new and useful Automatic Electrical Circuit Controller, of which the following is a specification, reference being had to the accompanying drawings, and to the letters and figures of 10 reference marked thereon.

This invention relates to the automatic control of electrical currents, more particularly to the control of an electrical current to transformers, and the invention relates 15 especially to the automatic switching of an electrical current through a resistance to a transformer and subsequently conducting the electrical current directly to the transformer.

20 An object of the invention is to eliminate faulty electrical connections and consequent trouble arising from unreliable or inefficient manual manipulation or operation of switching or controlling appliances, more 25 particularly in the operation of X-ray apparatus.

Another object is to enable operators of 30 X-ray apparatus to reliably obtain the maximum efficiency in the operation of the apparatus, and without liability to derangement or injury to the apparatus resulting from 35 inaccurate or faulty manual manipulation of controlling devices.

A further object is to provide an automatic 40 electrical circuit controller to control an alternating electrical current to the greatest advantage through a transformer and an X-ray tube, the alternating electrical current being graphically a more or less perfect sine wave, the voltage rising from zero 45 at the start to maximum as the peak of each half-cycle is reached; and consequently, when alternating current is turned directly into a transformer, especially high voltage 50 transformers of some types, such as those used for X-ray work, the transformer is subjected to an excessive amount of stress in case the peak of the wave or highest point 55 of voltage of supply current be in action at the moment the controlling switch is closed; and, the switch hitherto having been manually and haphazardly operated, if by chance 60 the switch is closed at the moment the voltage is at the wave peak or highest voltage 65 point the sudden surge of maximum voltage

which may result, is to be prevented by the present invention from passing into the transformer; an aim being to provide a system including a resistance and means to automatically, when a controlling switch is 60 closed, to conduct an electrical current first through the resistance momentarily to a transformer and subsequently to conduct the current directly to the transformer, and without requiring the objectionable method 65 of manually manipulating any controlling device after closing the switch, an objection to such manual control being that the operator may neglect to properly operate such device and consequently the transformer may 70 not get the full required voltage with the result that its power may be proportionately reduced, another result being that the resistance which may be used may be burned 75 out with consequent loss of time, trouble and expense.

With the above-mentioned and other objects in view, the invention consists in a system and means for momentarily reducing the voltage of an electrical current in its 80 passage to a transformer and means to automatically act to control the electrical current; and, the invention consists also further in the novel features and in the parts and combinations and arrangement of parts, 85 as hereinafter particularly described and further defined in the appended claims.

Referring to the drawings,—Figure 1 is an elevation of the preferred circuit controller and diagram of an electrical system, the controller being represented as inactive; Fig. 2 is a curtailed view similar to the preceding figure but showing the controller as in its first stage of action; Fig. 3 is a view similar to the preceding figure but with the 95 controller represented as in its final stage of activity.

In the various figures of the drawings similar reference characters indicate corresponding elements or features of construction herein referred to in detail.

In order to clearly illustrate the invention, its mode of operation and one of the useful and advantageous applications thereof, so much of an X-ray apparatus as may be associated with the invention is shown in the drawings and comprises an X-ray tube 8 and a transformer 12, a high tension circuit 13 leading from the transformer to the X-ray tube.

Preferably the electrical circuit controller structure is produced as a unit on a suitable base, a solenoid 18 is suitably arranged and its armature 19 has an insulating end 20 as 5 preferably constructed, the armature preferably being cylindrical and vertically arranged; and below the solenoid a stop bracket 21 is suitably supported and if not insulated is provided on its top with an insulation 22 arranged opposite to the insulating end of the solenoid armature. A suitable electrical resistance device is provided and preferably has a core 23 vertically arranged at a distance from the stop bracket, 10 an electrical resistance coil 24 being properly arranged on the core. A long elastic electrical switch arm 25 is suitably supported at one end and extends across the stop bracket but at a distance therefrom, the elasticity of the arm permitting it to be forced down by the solenoid armature to the stop bracket. A base 26 is suitably supported and has an elastic electrical switch finger 27 thereon that extends opposite to the arm 25 15 so that electrical connection may be made between the finger and the arm, the arm and the finger preferably having contact points 28 and 29 respectively, which are not in contact when the arm 25 is resting on the stop bracket, but are in contact when the arm moves a suitable distance away from the bracket. An electrically conducting plate 30 is suitably supported in proximity to the stop bracket and it has a lateral projection 20 31 thereon which is provided with a contact point 32 which preferably is adjustable in the projection and is engaged by the switch arm 25, or a contact point 33 on the arm when the solenoid armature releases the switch arm, the latter being free to move at 25 a short distance from the conducting connector plate 30. A circuit wire 34 is connected with the contact point 32 and with one end of the primary coil 35 of the transformer. A feed circuit wire 36 is connected with a suitable generator or source of electrical energy 37 and is connected also with the switch arm 25. A circuit wire 38 is connected with one end of the resistance coil 24 30 and also with the base 26 of the switch finger 27. A circuit wire 39 is connected with the opposite end of the resistance coil and also with the connector plate. A branch wire 40 is connected with the feed wire 36 and also 35 with one end of the winding of the solenoid 18, another wire 41 being suitably connected with the solenoid winding and with one side of a suitable switch 42 symbolically illustrated in the drawings, in practice the switch being usually outside of the cabinet of the apparatus. A return wire 44 is connected with the opposite end of the primary coil 35 of the transformer and is connected with the opposite side of the switch and also 40 with the source of current supply by means 45 of a branch 45. The feed wire 36 and the return wire branch 45 in practice are arranged in a cable so as to extend outside of the cabinet of the apparatus.

In practical use, the circuit switch 42 being open, as shown in Fig. 1, the solenoid armature is lowered and rests upon the switch arm 25 which is supported on the stop bracket 21, the arm 25 being separated from the switch finger 27 and also from the contact point 32. Upon closing the circuit switch 42, as in Fig. 2, the current energizes the solenoid to cause the armature to be drawn in, permitting the switch arm 25 to spring up slightly until contact is made with the finger 27, when the current passes from the arm to and through the finger 27, through the wire 38 and thence through the resistance coil 24, following the wire 39 and through the contact plate 30, and thence 50 through the wire 34 to the primary coil of the transformer, momentarily reducing the voltage of the current while the solenoid armature rises further and permits the arm 25, without breaking connection with the finger 27, to travel further and make connection with the contact point 32; and thus the electrical current instead of continuing to pass through the resistance coil follows the line of least resistance through the 55 switch arm 25 and the contact point 32 to the transformer through the wire 34.

Having thus described the invention, what is claimed as new is—

1. An automatic electrical circuit controller including a resistance coil, an elastic supported switch finger in connection with the resistance coil, a supported connector having a contact-point, a circuit connecting the resistance coil with the connector, a circuit in connection with the contact-point, a supported switch arm to be elastically pressed to the switch finger and farther to the contact-point, a feed-wire leading to the switch arm, and a solenoid having an armature arranged to control the switch arm. 100

2. In an automatic electrical circuit controller, the combination of a vertical resistance core, an electrical resistance coil on the core, an elastic switch finger supported above the resistance core and electrically connected with one end of the resistance coil, an elastic switch arm supported by the resistance core and extending under the switch finger, said arm being elastically pressed to 115 said finger and extending beyond the finger, a supported stop below the switch arm, a feed-wire connected with the supported portion of the switch arm, a connector plate supported adjacent to the unsupported end 120 of the switch arm and having a contact point to be engaged by the switch arm when the arm is in contact with said finger, a circuit wire connected with the opposite end 125 of the resistance coil and with the connector 130

plate, a feed-wire connected with said contact point, and a solenoid supported above said stop and said switch arm and having an armature vertically movable to hold said switch arm to said stop and away from said contact point and said switch finger.

3. In an automatic electrical circuit controller, the combination with two supported contact devices, of a resistance coil constantly connected in circuit with the contact devices, a circuit wire connected with one of the contact devices and thereby with the resistance coil, a feed wire to be connect-

ed with the remaining one of the contact devices, a switch element movably supported and adapted to electrically connect the feed-wire with the two contact devices successively, and an electro-magnet connected with the feed-wire and having an armature arranged to control the switch element.

In testimony whereof, I affix my signature in presence of two witnesses.

EDWIN L. EDWARDS.
